D. Morrison

Converting Rotary into Reciprocating Motion.

Nº 71506

Patented Nov. 26, 1867.

Inventor.

Duncan Morrison.

United States Patent Office.

DUNCAN MORRISON, OF PORTLAND, MAINE.

Letters Patent No. 71,506, dated November 26, 1867.

IMPROVEMENT IN APPARATUS FOR CONVERTING ROTARY INTO RECIPROCATING MOTION.

The Schedule referred to in these Letters Patent and making part of the same.

TO ALL WHOM IT MAY CONCERN:

Be it known that I, DUNCAN MORRISON, of Portland, in the county of Cumberland, and State of Maine, have invented a new and improved Apparatus for Converting Rotary into Reciprocate Motion; and I hereby declare the following to be a full, clear, and exact description thereof, which will enable others to make and use my invention, reference being had to the accompanying drawings, forming part of this specification, in which—

Figure 1 shows a side elevation of my invention.

Figure 2, an end elevation of the same.

My invention consists of the combination of a swinging weighted arm moving a horizontal shaft, upon which is rigidly set a geared wheel, with a second shaft and gear, there being upon this second shaft a wheel, from whose motion or revolution movement is imparted to the saw. The weighted arm or lever has a horizontal handle, by which it is first set in motion.

My invention also consists of a device for throwing the two geared wheels out of gear when desired.

I will now more particularly describe my invention, and make particular reference to the accompanying drawings.

A shows a frame or support, upon which the devices comprised in my invention are set. b shows the swinging arm, and a the weight on the lower end thereof. This arm is rigidly attached to the shaft c, so that the swinging of the arm gives a corresponding motion to the shaft. d shows the gear on the shaft c, and e that on the shaft f. The ends of these shafts rest in boxes provided for their reception, and indicated in the drawings. h shows a wheel rigidly attached to the end of the shaft f. On the side of this wheel are made holes for the reception of the bent end of the connecting-rod i, which is united with the saw-frame k. By swinging the weighted arm b, by means of the hand-lever m, motion is imparted to the shaft c, thence, by the gears d and e, to the shaft f, and thence, by the wheel h and connecting-rod i, to the saw-frame k. The swinging motion of the weighted arm b is thus made to move the saw upward and downward alternately. The movement of the saw-frame is regulated by guide-rods n, set vertically in the brackets o o. As considerable force must be exerted to stop the motion of the weighted arm b when once in motion, it is more convenient to have a means of separating the two gears d and e when it is desired to stop the motion of the saw. This I effect by means of the lever p and sliding bed r, upon which one end of the shaft f is placed. This lever is connected with the bed by the bolt s, and has its fulcrum on the bolt t, set into the main frame. By pushing the lever backward, the bed r so moves as to separate the wheels e and d, and thus check the movement of the saw-frame k.

My invention is intended to be operated by hand by means of the lever m. By first imparting the swinging motion to the weighted arm, and continuing the same, motion is given to the saw-frame k and the saw therein.

The sweep of the frame k can be increased or diminished by the relative diameters of the gears d and e, and by the different positions, relative to the centre, at which the connecting-rod i is united with the wheel h.

I am aware of Letters Patent to A. Slevin, March 30, 1858, and William Barnheard, April 13, 1825, and I do not claim a weighted swinging arm or pendulum for the purpose of causing a rotary motion; neither do I claim the combination of two gears and shafts; neither do I claim moving the saw by a crank.

What I claim as my invention, and desire to secure by Letters Patent, is—

The arrangement of the several devices hereinbefore described, to wit, the swinging arm a b, shaft c, gear d, shaft f, wheel h, gear e, connecting-rod i, saw-frame k, lever p, bed r, in and upon the frame A, to constitute a convenient means of working a wood-saw, substantially as specified.

Witnesses:

WILLIAM HENRY CLIFFORD,
HENRY C. HOUSTON.

DUNCAN MORRISON.
